UNITED STATES PATENT OFFICE.

NOAH S. HARTER, OF WAUKEGAN, ILLINOIS, ASSIGNOR TO THE HARTER COMPANY, OF WAUKEGAN, ILLINOIS, A CORPORATION OF ILLINOIS.

FUEL-REGULATOR.

1,178,155.

Specification of Letters Patent.

Patented Apr. 4, 1916.

Application filed January 18, 1915. Serial No. 2,817.

To all whom it may concern:

Be it known that I, NOAH S. HARTER, a citizen of the United States, residing at Waukegan, in the county of Lake and State 5 of Illinois, have invented certain new and useful Improvements in Fuel-Regulators, of which the following is a specification.

My invention relates to improvements in fuel regulators whereby to automatically 10 control the heat applied to cooking utensils.

One of the objects of my invention is to provide a separable heat-controlling device, that may be applied to the ordinary gas stove and to any of the usual containing vessels 15 or utensils used for cooking, whereby to automatically control the temperature within such vessel, by varying the gas supply.

Another and more specific object of my invention is to provide a separable heat- 20 responsive, fuel-controlling device, provided with flexible gas conduits, or hose, that may be introduced between the nozzle and burner of an ordinary gas stove and so arranged that the responsive device, attached thereto, 25 may be placed near or within the vessel, within which food is being cooked.

Other and further objects of my invention will become apparent to persons skilled in the art, from a consideration of the following description when taken in conjunction 30 with the drawings, wherein:

Figure 1 is a plan view of a one burner gas stove with a cooking utensil thereon and my heat regulating device applied thereto. 35 Fig. 2 is a central section taken on line 2—2 of Fig. 1. Fig. 3 is a transverse section taken on line 3—3 of Fig. 1. Fig. 4 is a section taken on line 4—4 of Fig. 1. Fig. 5 is a section taken on line 5—5 of Fig. 3. 40 Fig. 6 is a section taken on line 6—6 of Fig. 2.

In all the views the same reference characters are employed to indicate similar parts.

In the single embodiment which I have 45 chosen for the purpose of exemplifying my invention, 10 is a gas burner, of the single burner type, provided with a burner 11 having a gas and air eduction pipe 12, the outer end or mixing chamber 12' of which is normally supported upon the nozzle 13, the inner end, or burner, being supported upon a cross bar 14. A pipe 15 carries a needle valve 16 from which the nozzle 13 projects inwardly, provided with a hand wheel 17. 50 The pipe 15 is supported upon brackets 18

that project from the frame 19 of the stove 10. One end of the pipe 15 is provided with a cap 20, the other end is provided with a nipple 21 for attachment to a hose for connection to a suitable gas supply. The foregoing description will apply generally to gas stoves of the usual or well known type. 60

The prime object of my invention is to apply a fuel controlling mechanism, responsive to the heat within the cooking utensil, for controlling or regulating the gas supplied to the burner, when the heat within the vessel has reached a predetermined temperature or degree. 65

22 is a cooking vessel or utensil having a 70 cover 23 and a handle 24. Within this vessel, food is to be cooked.

The heat responsive device, or gas controller, is generally indicated by 25 and consists of a casing provided by the castings 75 26 and 28, secured together at their edges, as by screws. The casting 28 is provided with a gas inlet 27 to which is attached a hose 27'. A gas outlet 29 is also provided in said casting to which is attached the hose 80 29'. The passage-way 27 communicates with a vertically disposed recess 31 which is open at its bottom end, as at 32, and adapted to be closed by a diaphragm 33 which shuts off the passage between the recess 31 and 85 the passage way 27. The diaphragm 33 is secured around its circumferential edges in a recess in the casting 26 so that any heat applied to the diaphragm will tend to expand it and will cause it to close the aperture 32 of the recess 31, and thus close communication between the passage way 27 and the recess 31. When the diaphragm is relaxed, as shown in Fig. 3, there is an opening thereby provided between the end 32 of 90 the recess 31, and gas will then pass from the passage way 27 into the recess 31, between the diaphragm 33 and the opening 32, into the passage way 29, but when the diaphragm 33 is expanded, as by heat applied 95 to the bottom of the device, as shown by the arrows in Fig. 3, it will expand to a greater or less extent, and to that extent or degree it will close the opening, thereby throttling or regulating the gas supply that will pass from the hose 27' to the hose 29', through the regulator, as heretofore described. A screw 34 passes through the recess 31 into 100 and through the wall 35 between said recess and the passage way 29. The clearance 105

110

hole through the wall 35 is not threaded and therefore the gas that passes from the passage way 31 to the passage way 29 is not controlled by the action of the diaphragm 33. The gas that will pass from the recess 31 to the passage way 29 passes through the grooves provided by the screw threads on the screw and the clearance hole into which the screw is projected, and the farther the 10 screw is projected into the wall 35, to the extent of the thickness of the wall, the longer will be the path and greater will be the resistance of the passage of the gas through this path and therefore a smaller 15 amount of gas will pass into the hose 29'. The gas, controlled by the screw 34, is adapted to permit a variable but determined quantity of gas to always pass into the burner 11 without regard to the operation of the diaphragm, so that at no time can the diaphragm 33 so close the gas passage as to permit extinction of the flame at the burner.

The casting 26, of the responsive device 25, is provided with a downwardly projecting nub or stud 36 which is adapted to enter a hole 37 to be made in the cover 23 of the utensil 22. This hole is preferably somewhat larger than the projection 36 to permit steam or heat to pass up from the utensil 30 past the projection 36 and into contact with the bottom wall of the casting 26 thereby to heat the diaphragm to an extent determined by the heat within the utensil. The projection 36 also operates as a means for positioning and holding the responsive device 25 in proper position on the cover 23 to prevent its accidental displacement. Other means than that shown may be employed for holding the controlling device 25 in contact with any 35 wall of the cooking utensil 22, within the contemplation of my invention.

A convenient means for applying my device to an ordinary gas stove is to remove the mixing chamber 12' from the end of the 45 nozzle 13, and provide a bracket 39 preferably secured to the stove, as to the pipe 15, by a screw 40, and rest the end 12' on this bracket. I thereafter place the end 41 of the hose 27' upon the nozzle 13 of the stove 50 needle valve, and the nozzle 42' of the end 42 of the hose 29, inside of the mixing chamber 12', which was formerly occupied by the nozzle 13. It will now be observed that the 55 gas must pass from the pipe 15 through the needle valve 16 into the hose 27', through the passage way 27, and between the diaphragm 33 and the recess 31 through the opening 32 and from thence through the passage way 29, into the hose 29' and from 60 thence into the mixing chamber 12' of the burner 11.

The nozzle 42' is provided with a plurality of springs 43 that engage the walls of the orifice in the end of the mixing chamber 65 12' as a means for retaining the nozzle 42'

in place. To remove the nozzle it is only necessary to pull it out of the orifice in the mixing chamber 12', and the springs 43 will yield sufficiently for it to pass from the said orifice. To insert it, it is only necessary to press it firmly into the orifice, in the mixing chamber 12', when the springs 43 will yield and the outwardly bent ends 44 of the springs will control the distance to which the nozzle 42' enters the mixing chamber. 75

The casting 28, of the device, is provided with a hand piece 44, and a perforation 45 by which the device may be handled or hung up on a nail, or the like, out of the way when not in use. A knob 46, preferably of material which is not a good conductor of heat, such as wood or the like, is secured to the top of the device, by which it may be handled while in use, as when it is necessary to remove the cover 23 of the vessel 22. 85

While I have herein shown and described a single embodiment of my invention for the purpose of clear disclosure, it is manifest that considerable change in the general formation and disposition of parts may be 90 made within the scope of the appended claims.

Having described my invention, what I claim is:—

1. A device of the character described for 95 use with a gas stove and cooking utensil comprising a portable heat-responsive gas-controller; means comprising a thermal inductor for supporting said controller on said utensil, over an aperture therein, and flexible means for detachably connecting said device between the nozzle and burner of said stove.

2. A device of the character described for use with a gas stove and a cooking utensil 105 comprising a portable heat-responsive gas-controller; means thereon, comprising a thermal conductor for entering a perforation in the top of said utensil, to hold it in place; a hose for connecting the nozzle of 110 said gas stove with said device and another hose to connect the burner of said stove with said device.

3. A device of the character described for 115 use with a gas stove and a cooking utensil comprising a portable heat-responsive gas-controller; means thereon, comprising a thermal conductor for entering a perforation in the top of said utensil, to hold it in place; a hose for connecting the nozzle of 120 said gas stove with said device and another hose to connect the burner of said stove with said device and a supporting bracket fixed to said stove to hold the burner in place when removed from the stove nozzle. 125

4. A device of the character described, for use with a gas stove and cooking utensil comprising a portable heat-responsive gas controller, an expandable valve controlling chamber therein, a projection from a wall 130

of said chamber adapted to secure the controller in position on the cooking utensil and transmit heat to the said expansible chamber, a flexible conduit for supplying gas to the said controller and a second flexible conduit between the controller and burner of the gas stove.

In testimony whereof I hereunto set my hand in the presence of two subscribing witnesses.

NOAH S. HARTER.

In the presence of—

FRANK P. TYLER,

ALVAH L. ROGERS.
